UNITED STATES PATENT OFFICE.

MARTIN T. MINOGUE, OF PHILADELPHIA, PENNSYLVANIA.

REINFORCED MOVING-PICTURE-FILM DRIVE.

1,359,821.

Specification of Letters Patent. Patented Nov. 23, 1920.

Application filed November 10, 1919. Serial No. 337,101.

To all whom it may concern:

Be it known that I, MARTIN T. MINOGUE, a citizen of the United States, and a resident of Philadelphia, in the county of Philadelphia and State of Pennsylvania, have invented certain new and useful Improvements in Reinforced Moving-Picture-Film Drives, of which the following is a specification.

10 One object of my invention is to so reinforce the ordinary manufactured film to prevent breaking or fracture at the sprocket holes or breaking otherwise during the operation of same, thus greatly adding to the 15 wear and usefulness of the film.

20 A further object of my invention is to so reinforce a moving picture film as to render it practically non-breakable in actual use thus maintaining a synchronism between the 25 moving picture and a talking machine, working in conjunction with each other.

These objects I attain in the manner hereinafter set forth. Reference had to the accompanying drawings in which:—

25 Figure 1 is a piece of film reinforced with a single filament or strand at each row of sprocket holes. Fig. 2 is a piece of moving picture film reinforced with two filaments or strands of material at each row of the 30 sprocket holes. Fig. 3 is a longitudinal cross section of a piece of moving picture film showing the filament or strand interwoven longitudinally through the sprocket holes of the film. Fig. 4 is a cross section of a 35 sprocket spool driving a film reinforced with one filament. Fig. 5 is a cross section of a sprocket spool driving a film reinforced with two filaments.

In Fig. 1 of the drawing 1 represents a 40 piece of film of the regular manufacture with the proper sized and spaced sprocket holes through which a single filament 2 of thread, fine cord of any material desired, fine metal wire of steel or copper is woven 45 longitudinally of the entire length of the reel of film. A sprocket spool 3 provided with suitable teeth 12 is used to properly engage the sprocket holes in the film 1. A central groove 11 in the sprocket teeth 12 50 allows the filament 2 to travel in said groove 11. The groove is wider at the top of the teeth and extends to a depth just below the base of the sprocket teeth 12. The filaments or strands are woven into the holes of the 55 film 1 longitudinally from one sprocket hole to another and so the spaces 14 and 15 are

divided. One half of the film spaces 14 are above the filament and the other half of the spaces 15 are below the filament and are clamped against the surface of the spool 60 sprocket as it travels over same by the filaments riding on top of spaces 15. The next film space 14 being on top of the filament 2 the filament will travel in the groove 11 in the center of the sprocket wheels, thus 65 providing a belt drive by the combined friction of the film 1 and the filament 2. The sprocket holes serve only in the capacity of timing the pictures by the intermittent gear. The groove 11 being slightly under the surface of the sprocket spool and deeper than 70 the base of the sprocket teeth provides for a strong clamping surface, as filament 2 presses spaces 15 against the surface of the spool sprocket. Also the filament or strand 75 which is on the under side of the spaces of the film between the sprocket holes rides in the grooves 11 and allows the film 1 to adhere to the surface of the spool sprocket as it travels over same. 80

Fig. 2 of drawing is the regular manufactured film with two filaments 5 and 6 interwoven in sprocket holes longitudinally from hole to hole, separated and each resting at the opposite sides of the sprocket holes, otherwise it is similar to the reinforced film described in Fig. 1 with the exception that the film rests at the sides of the sprocket holes and not in the center. The teeth 16 being 85 wedged shape on the sides and coming to a point on the top keeps the filaments separated and guides them to the grooves 8 and 9 around which they travel. The making of the double filament is similar to that of the single filament explained in Fig. 1. The 90 object of the double filament is to provide greater strength and friction drive.

While I have described a reinforced film and drive, with a single and a double filament passing through the sprocket holes of 100 the entire length of a film reel, I do not confine myself to any particular number of filaments that may be used for reinforcement, providing the driving sprockets are so made to receive and drive them properly, neither 105 do I confine myself to any particular material for the filaments or strands but they must be small in diameter, strong and very flexible with a very limited amount of stretching quality, such as linen thread or 110 cord, copper or steel wire. Neither do I confine myself to the method of attaching the

filaments to the film. It can be woven from one hole to another as explained or holes can be skipped and filaments passed through holes at any given length or desired distance. 5 It can be placed on one or both sides of the film longitudinally with the sprocket holes and attached to the spaces of film between the sprocket holes in any well known way, or it can be a part of the manufactured film 10 in which the filaments are embedded in the film bridging across sprocket holes or at the sides of same. Fig. 3 of drawing shows how the filaments or strands are woven longitudinally from one sprocket hole to another. 15 Fig. 4 of drawing shows a sprocket spool 3 to drive a single filament in each of the series of sprocket holes in each side of the film 1. This sprocket 3 has a central groove 10 and 11 in the sprocket teeth 12 to receive 20 the filaments 2 and 2. Fig. 5 of the drawing is a sprocket spool 7 to drive a double filament as explained in Fig. 2 with film 4. The sprocket teeth 16 are formed with angle sides 25 pointed at the top to divide the filaments 5 and 6 terminating at the base with grooves 8 and 9, the filaments 5 and 6 traveling in the grooves 8 and 9 between the sprocket holes of the film.

I desire to call attention to the synchronism of the moving picture to the talking machine. The great drawback encountered to properly synchronize the two machines is on account of the breaking of the picture film. A complete picture directly attached 30 to a talking machine with a complete record of the picture will synchronize continuously as long as there is no breakage or mechanical interruption of either the picture or the record, and can be run as often as desired, the 35 synchronism always maintained and complete. But with a frail film with unprotected sprocket holes to easily break by the driving of the sprocket teeth, breaking and tearing out the spaces between the sprocket 40 holes, the timing of the picture with the talking machine is lost. Therefore with my invention of a reinforced film and drive preventing breakage and fracture of film a 45 synchronism is constantly maintained between the moving picture and the talking machine. In the use of my invention of a

non-breakable film and drive, with the ordinary projecting machines, it is only necessary to remove the spool sprockets of the machine and replace them with the proper spool 55 sprockets of my invention, which will not only drive and time the reinforced film, but will also drive and time the ordinary film that has not been reinforced.

Having thus described my invention I 60 claim:—

1. The combination of a moving picture film reinforced with a flexible driving belt of any suitable material, passing longitudinally across the sprocket holes and interwoven 65 through the same, a sprocket spool having a series of teeth to engage the sprocket holes of the film, the sprocket teeth being formed to properly receive the flexible driving belt.

2. The combination of a moving-picture 70 film reinforced with a single filament or strand of any suitable material passing longitudinally in the center of sprocket holes of the moving picture film, said filament or strand interwoven through the sprocket 75 holes, half of the spaces of the film between the sprocket holes being above and the other half below said filament or strand, a sprocket spool having a series of teeth to engage the sprocket holes of the film, the sprocket teeth 80 having a groove in center of said teeth to receive said filament or strand and drive said filament and moving picture film as described.

3. The combination of a moving picture 85 film reinforced with a flexible driving belt or filament passing longitudinally across the sprocket holes and interwoven through the same, a sprocket spool having a series of teeth to engage the sprocket holes of the 90 film, the teeth of said sprocket spool being so formed to properly receive the driving belt or filament, said formation of sprocket teeth being lower than the outer surface of the sprocket spool as described.

In testimony whereof, I have signed my name to this specification in the presence of two subscribing witnesses.

MARTIN T. MINOGUE.
